UNITED STATES PATENT OFFICE

130,816

DESIGN FOR A RIFLE BRACKET

William B. Johnson, United States Army

Application October 22, 1941, Serial No. 103,864

Term of patent 3½ years

To all whom it may concern:

Be it known that I, Lieutenant Colonel William B. Johnson, Quartermaster Corps, United States Army, Holabird Quartermaster Depot, Baltimore, Maryland, a citizen of the United States, residing at Holabird Quartermaster Depot, Baltimore, and State of Maryland, have invented a new, original, and ornamental Design for a Rifle Bracket, of which the following is a specification, reference being had to the accompanying drawing, forming part thereof.

Fig. 1 is a side elevational view of a rifle bracket, showing my new design, and

Fig. 2 is a front elevational view thereof, and

Fig. 3 is a side elevational view of the opposite side of the rifle bracket.

I claim:

The ornamental design for a rifle bracket, as shown.

WILLIAM B. JOHNSON.
